J. A. PETRIE,

SAND WHEEL TOY.

APPLICATION FILED FEB. 26, 1917.

1,247,145.

Patented Nov. 20, 1917.

UNITED STATES PATENT OFFICE.

JOHN A. PETRIE, OF NEW HAVEN, CONNECTICUT.

SAND-WHEEL TOY.

1,247,145.

Specification of Letters Patent. Patented Nov. 20, 1917.

Application filed February 26, 1917. Serial No. 150,916.

To all whom it may concern:

Be it known that I, JOHN A. PETRIE, a citizen of the United States, residing at New Haven, in the county of New Haven and State of Connecticut, have invented a new and useful Improvement in Sand-Wheel Toys; and I do hereby declare the following, when taken in connection with the accompanying drawings and the characters of reference marked thereon, to be a full, clear, and exact description of the same, and which said drawings constitute part of this application, and represent, in—

Figure 1 a view in elevation of my improved sand-wheel toy with portions of the sand pail and combined pail-cover and sand-wheel base broken away.

Fig. 2 a detached view in elevation of the sand-wheel frame, the sand wheel being shown at a right angle to the position in which it is shown by broken lines in Fig. 1.

Fig. 3 a detached view of the sand wheel which is shown at a right angle to the position in which it is shown in Fig. 1.

Fig. 4 a view partly in elevation and partly in section, of the toy assembled and in operation.

Fig. 5 a detached plan view of the sand-wheel frame.

Fig. 6 a detached perspective view of the sand-wheel hub.

Fig. 7 a corresponding view of one of the sand-wheel buckets.

My invention relates to an improvement in sand-wheel toys, the object being to produce a simple, compact, durable, attractive and interesting sand-wheel toy constructed with particular reference to being easily set up for use and as easily assembled for transportation.

With these ends in view, my invention consists in a sand-wheel toy having certain details of construction and combinations of parts as will be hereinafter described, and pointed out in the claims.

In carrying out my invention as herein shown, I employ a tapered bottomless sand pail 2 having an ordinary bail handle 3. This pail receives the sand when the toy is in use, and when not in use constitutes a housing for the sand-wheel frame which is constructed to fit into it, and which comprises, as shown, a circular flanged combined pail-cover and wheel-base 4, a circular flanged pail-bottom 5 formed with a perforation 6 through which the sand flows, and three in-

clined uprights 7 permanently connecting the said parts 4 and 5 within the flanges thereof. A horizontal shaft 8 extending between the two oppositely located uprights 7 mounts the sand-wheel which consists, as shown, of a wooden hub 9 formed with regularly spaced radial slots 10 receiving the inner ends of sheet-metal sand-buckets 11. Sleeves 12 and 13 upon the shaft 8 position the wheel thereon under the perforation 6 in the pail-bottom 5 the flange of which is formed with an outwardly turned edge 14 upon which the lower edge of the bottomless sand-pail 2 rests when the toy is in use. A pulley 15 on the shaft 8 provides means for utilizing the power of the sand-wheel for driving other toys, if desired.

For transporting the toy from place to place, the sand-wheel frame is turned upside down, as it were, and inserted into the pail 2 as shown in Fig. 1, the combined pail-cover and base 4 then fitting over the top of the pail and the pail-bottom 5 closing the bottom of the pail. To use the toy, the sand-wheel frame is removed from the pail, and reversed in position after which the open bottom of the sand-pail is set down over the flanged sand-pail bottom 5 so as to rest upon the edge 14 thereof as shown in Fig. 2. The pail 2 is now filled with sand which, running through the perforation 6 in the pail-bottom 5, falls in a stream upon the buckets 11 of the sand-wheel and rotates the same, this continuing until all of the sand has run out of the pail.

It will be seen that my improved sand-wheel toy is limited to two permanently organized structures, viz., a pail-structure, and a wheel-structure in which a sand-wheel is permanently mounted in position for use. Neither of these two structures requires adjustment to adapt them for use, beyond placing the pail-structure upon the wheel-structure.

I claim:—

1. In a sand-wheel toy, the combination with a bottomless sand pail, of a sand-wheel frame adapted to be housed therein and comprising a combined pail-cover and sand-wheel base, a pail-bottom, and supports uniting the said parts; and a sand-wheel mounted in the said supports.

2. In a sand-wheel toy, the combination with a bottomless sand pail, of a sand-wheel frame adapted to be housed therein and comprising a combined pail-cover and sand-

wheel base, a pail-bottom, uprights connecting the said parts; a shaft mounted in the said uprights, and a sand-wheel mounted upon the said shaft.

5 3. In a sand-wheel toy, the combination with a bottomless sand pail, of a sand-wheel frame comprising a combined pail cover and sand-wheel base, a perforated pail bottom, inclined uprights connecting the said parts, 10 and a sand-wheel mounted between the said uprights and consisting of a radially slotted hub, and buckets inserted into the slots therein.

4. A sand-wheel toy having a bottomless 15 pail, and a permanently organized wheel-structure adapted to be housed therein and comprising a combined pail-cover and sand-

wheel base providing a cover for the pail when the toy is not in use and a base for supporting the toy when in use as a sand-wheel 20 toy, a pail-bottom for closing the bottom of the pail when in use, means for permanently spacing the said combined cover and base and pail-bottom at a fixed distance apart, a wheel, and means for mounting the same in 25 the vertical axis of the pail between the said cover and base in the said spacing means.

In testimony whereof, I have signed this specification in the presence of two subscribing witnesses.

JOHN A. PETRIE.
